CLAIM

The ornamental design for the portable medical trailer, as shown and described.

DESCRIPTION

FIG. 1 is a front elevational view of the portable medical trailer in accordance with an embodiment of the present invention;

FIG. 2 is a right side view thereof;

FIG. 3 is a rear elevational view thereof;

FIG. 4 is a left side elevational view thereof;

FIG. 5 is a top plan view thereof;

FIG. 6 is a bottom view thereof;

FIG. 7 is a perspective view thereof;

FIG. 8 is a right end view showing the doors in the open position; and,

FIG. 9 is a left end view showing the doors in the open position.

The broken line is included for purposes of illustrating portions of the article and forms no part of the claimed design.
